COLLAPSIBLE TUBE CLOSURE

John Dieckmann, Edna W. Dieckmann, and
Herbert Lodde, New York, N. Y.

Application August 25, 1938, Serial No. 226,736

2 Claims. (Cl. 221—60)

Our invention relates to improvements in collapsible tubes, particularly to a method of closing the filler ends of the same, as for instance disclosed in our Patent No. 2,094,877 issued October 5, 1937, particularly used for the closing of tubes used for packing of food preparations of a delicate nature, as for instance caviar and anchovy paste, the taste and salubrity of which is easily destroyed or injured when the tube closure is not effected in an efficient and thoroughly hygienic manner.

It is the principal object of this invention to provide in addition to the closing of the tube by either cold or hot solder as described and claimed in our above identified patent, a method of closing the filler end of the tubes by folding or crimping the walls of the tube, and/or by means of suitable clips or the like and then soldering the folded, crimped or clipped ends.

Another object of our invention is the provision of a tube closure well adapted for the closure of open and also of closed tubes.

Still another object of our invention is the provision of a tube closure by the insertion of a very thin or fine wire held between the compressed ends of the filler tube end by hydraulic or other pressure and by soldering, folding, crimping or clipping the tube end.

A further object of our invention is the provision of a paste tube closure which is durable and highly efficient as well as sanitary in every respect.

A still further object of our invention is the provision of a paste tube closure, the folding, crimping, clipping and soldering of which may be effected by any suitable apparatus to provide an efficient and lasting closure.

These and other objects and advantages of our invention will become more fully known as the description thereof proceeds, and will then be specifically defined in the appended claims.

In the accompanying drawing forming a material part of this disclosure:

Fig. 1 is an elevation of a tube having its compressed, and folded end inserted in a solder bath.

Fig. 2 illustrates the crimped and soldered end of the tube.

Fig. 3 shows the attachment of a clip holding the tube ends together and soldered thereto.

Fig. 4 shows a wire insert.

As illustrated, the collapsible tube 10 comprises the usual cap 11 for closing the discharge end thereof. The filler end walls 12 are tightly compressed and then folded, as at 13, and then sol-

dered in a suitable bath. Or, the tube end is crimped, as at 14, and then soldered, as at 15. As shown in Figure 3 a suitable clip may be attached to close the folded or unfolded tube end, as at 16, which is then soldered to the tube end. As shown in Figure 4 a thin wire 17 is inserted between the end walls and is then intimately held in place by hydraulic or other pressure whereupon the application of a suitable solder will effect a perfect closure of the tube.

It will be clear that the inner walls of the tube before their compression and soldering, or folding, crimping and clipping and then soldering, must be scrupulously cleaned, and that the folding, crimping, clipping and wire insertion can be effected by any suitable apparatus in order to produce a perfectly sanitary and secure closure of the filler end of a tube.

Our method therefor consists in first cleaning and compressing the filler end walls, then folding or crimping the same, or attaching a clip and then soldering the folded, crimped or clipped tube end, and/or inserting a wire of suitable material and preferably very thin between the tube ends and uniting the same by strong pressure and solder. We may use this method of closing collapsible tubes for tubes which are either open or which have been previously closed by any of the methods used for this purpose.

It will be understood that we have described and shown the preferred form or ways of practically carrying out our invention as a few examples of the many possible ways to practically embody our invention, and that we may make such changes in the construction in general and in the individual steps as come within the scope of the appended claims without departure from the spirit of our invention and the principle involved.

Having thus described our invention, what we claim as new and desire to secure by Letters Patent, is:

1. A method of closing collapsible tubes consisting in inserting a light wire between the end walls of the tube's filler end and compressing said end walls to embed the wire firmly between the same, and finally soldering.

2. As an article of manufacture a collapsible tube comprising a thin wire insertion between the compressed filler end walls of the tube and a solder closure.

JOHN DIECKMANN.
